United States Patent Office

Des. 195,799
Patented July 30, 1963

195,799

STAPLING MACHINE

George P. Heilman, Herrin, Ill., assignor to International
Staple and Machine Company, Herrin, Ill., a corpora-
tion of Pennsylvania

Filed Apr. 14, 1961, Ser. No. 64,740

Term of patent 14 years

(Cl. D74—1)

FIG. 1.

FIG. 2.

FIG. 3.

FIG. 1 is a side perspective view of a stapling machine showing my new design, the side opposite thereto being similar in appearance;

FIG. 2 is a front perspective view; and

FIG. 3 is a rear perspective view thereof.

I claim:

The ornamental design for a stapling machine, sub-
stantially as shown and described.
